DISPENSING CONTAINER FOR MARGARINE OR THE LIKE

Richard L. Gannett and Jeffrey L. Ashby, Dallas, Bruce E. Welsh, Jr., and Daniel A. Leo, Richardson, and Carlton W. Howorth, Dallas, Tex., Robert E. Corba, Racine, Wis., and Robert N. Carow and James M. Beck, Chicago, Ill., assignors to Anderson, Clayton & Co., Houston, Tex.

Filed Sept. 29, 1972, Ser. No. 293,358

Term of patent 14 years

Int. Cl. D9—01

U.S. Cl. D9—9

FIG. 1 is a front elevational view of a dispensing container for margarine or the like showing my new design;

FIG. 2 is a bottom view thereof;

FIG. 3 is a top plan view thereof; and

FIG. 4 is an elevational view thereof looking from the right of FIG. 1.

We claim:

The ornamental design for a dispensing container for margarine or the like, substantially as shown.
